*J. Edgecomb,
Boring Wood.*

Inv. No 43,364.

Patented June 28, 1864.

Inventor:

Joseph Edgacomb -
by his Attorney
Thos H. Dodge -

UNITED STATES PATENT OFFICE.

JOSEPH EDGEcomb, OF WORCESTER, MASSACHUSETTS, ASSIGNOR TO
THOMAS H. DODGE, OF SAME PLACE.

IMPROVEMENT IN BORING-MACHINES.

Specification forming part of Letters Patent No. 43,364, dated June 28, 1864.

To all whom it may concern:

Be it known that I, JOSEPH EDGEcomb, of the city and county of Worcester, and State of Massachusetts, have invented certain new and useful Improvements in Boring-Machines; and I do hereby declare that the following is a full, clear, and exact description of the construction and operation of the same, reference being had to the accompanying drawings, in which—

Figure 1 represents a front view of said machine. Figs. 2 and 3 represent longitudinal vertical sections through the same. Fig. 4 represents a horizontal section through the frame of the machine. Fig. 5 represents a detached view, hereinafter to be referred to.

My invention relates to the application of certain devices to boring-machines, whereby the penetrating motion of the auger is stopped at a certain point to break the thread in the wood, and is raised or withdrawn from the hole automatically while the machine is in operation, thereby obtaining a perfect bore and greatly facilitating the operation.

To enable others skilled in the art to make and use my invention, I will proceed to describe its construction and operation.

A represents the frame of the machine. It is of semi-cylindrical shape, widening near its lower end, where it is hinged at a to block or bed B. It can be turned down on said hinge to make it convenient for transportation and for boring angular holes. When raised up, as represented in the drawings, it is held in its vertical position by the clamp-screws b, which pass through the slotted standards C of the bed B.

D represents a carriage, which can slide vertically on the ways c of the frame A. It supports the horizontal crank-shaft E by which the bevel-wheel F is turned, and also the vertical auger-shaft G, which is operated by the bevel-pinion H.

I represents an ordinary gear-wheel, which is secured to the crank-shaft E, and which gears with the rack K. The latter is pivoted at its lower end, d, to the frame A, while its upper end enters a recess, f, at the upper end of the frame, where the spiral spring g presses it toward the front of the frame, as seen in Fig. 3. The upper part of the rack K is

curved, for purposes to be explained in the operation of the machine.

L represents a cylindrical spring-rod, which passes through the lugs u of the rack K, and whose forked upper end bears against either of the shoulders 1 or 2 of the projection h, as shown in dotted lines in Figs. 2 and 3 and in full lines in the detached section at Fig. 5. It is pressed upward against said projection by the action of the coiled spring v, which bears against the upper lug, u, and against the shoulder 3 of the rod L.

m represents a screw-thread on the crank-shaft E, which terminates in a cam, n, and which operates a dog, o, secured to the spring-rod L.

M represents a stop, which can be adjusted on the edge of the frame A, and can be secured in any desired position by means of the set screw p, (shown in Fig. 4,) and its object is to arrest the motion of the sliding carriage at a certain point, where the penetrating motion of the auger has to stop, to cut the thread in the wood. The edges or ways c of the frame A are graduated, so that the stop M may readily be adjusted according to the depth of the hole to be bored. The dog o on the spring-rod L is also made adjustable thereon by means of the screw q, and the method of adjusting it will be fully understood from the operation of the machine.

The operation of the machine is as follows: The machine is placed upon the stick to be bored, and the auger properly adjusted, together with the dog o and stop M, when the operator, by means of the cranks N, turns the wheel I toward him until said wheel has passed down below the upper curved part of the rack K and becomes entirely free thereof, as indicated in red lines in Fig. 2. The gear I now being free from rack K, and the auger resting upon the piece to be bored, the operator reverses the motion of the cranks N, and the auger enters the wood, the same as in an ordinary boring-machine, and continues until the lower edge, x, of the carriage D comes in contact with the stop M, when its descending motion and the penetration of the auger is arrested, and it commences to cut the thread in the wood. At this instant the dog o, having been properly adjusted, is acted upon by the

screw *m* on shaft *E*, is turned toward the center of the machine, and is finally pressed down by cam *n*, as shown in Fig. 3. Thus the rod *L* is pressed down, and its upper end descending so as to clear the shoulder 2, Figs. 2, 3, and 5, the coiled spring *g* causes the rack *K* to fly forward and to come in gear with the wheel *I*, the upper end of the rod *L* being stopped by the shoulder 1 on projection *h*, as shown in red lines in Fig. 5, and as the cranks *N* are further turned the carriage *D* and the auger are raised by the action of the wheel *I* on rack *K*, as shown in Fig. 2, and while thus rising the wheel *I* presses against the upper curved part of the rack *K* and pushes it back, together with the rod *L*, which is connected with it, until the wheel *I* has passed the uppermost cog of the rack, when the latter and the rod *L* is sprung again behind the shoulder 2 of the projection *h*, and as the rod *L* is pressed upward by the action of the spring *v* the rack *K* will again be secured in a position where it will be out of gear with the wheel *I*, when the latter is brought down over the uppermost cog of the rack *K*, and the operation of boring can be renewed, as above described. The upper end of the spring *v* is secured to the rod *L*, while the lower end presses upon the rack *K*. The rod *L* thus has a tendency to turn or twist by the action of said spring, and when the dog *o* has been pressed toward the center by the screw *m* it is sprung back by the action of the spring *v* as soon as it has cleared the cam *n*. Stop *M* is provided with a steel point, 6, which enters one of the notches on the side of the frame *A*, and, in combination with the screw *p*, forms a very neat and true device for arresting the descent of the auger.

The object of the curved part *K'* of the rack *K* is to hold the carriage *D* and auger up without any attention or fastening on the part of the operator.

It will be observed that the gear *I*, when

fully up, is pressed by the uppermost cog on the rack-bar below its center, and in such a manner as to give the gear *I* a tendency to move up still higher. It will also be observed that the upper end of the rack-bar *K* is allowed to spring forward considerable after the center of gear *I* has passed the upper cog on *K*, before the upper end of rod *L* is arrested by its stop 2, which adds very much to the security of the device as a means of holding up the auger, as above described.

Having thus fully described the nature of my invention, what I claim herein as new, and desire to secure by Letters Patent, is—

1. The combination of the stop *M* with the device for automatically throwing into action the rack-bar *K* and gear *I* after the auger has made one or more revolutions to break the thread in the wood, substantially as and for the purpose herein described.

2. The combination of the screw *m*, cam *n*, and dog *o* with the spring-rod *L*, for the purpose of throwing the rack-bar in and out of gear from the wheel *I*, substantially in the manner herein described.

3. In combination with the rod *L*, the spiral spring *v*, for the twofold purpose of forcing said rod upward and of imparting to it a tendency to turn so as to force the dog *o* to its original position after it has been acted upon by screw *m*, substantially as herein described.

4. In combination with the stop *M*, the setscrew *p*, and point 6, when applied to boring-machines, substantially as herein described.

5. The combination of the auger-shaft *G*, bevel-wheels *F H*, wheel *I*, screw *m*, cam *n*, rack-bar *K*, spring *L* with the several devices for operating them, substantially as and for the purposes set forth.

JOSEPH EDGEcomb.
